UNITED STATES PATENT OFFICE

168,813

MERCHANTISE DISPLAY STAND

Gerhard J. Vetter, Milwaukee, Wis., assignor to
The Sanisco Display Company, Milwaukee, Wis.

Application May 11, 1951, Serial No. 15,147

Term of patent 14 years

(Cl. D80—9)

To all whom it may concern:

Be it known that I, Gerhard J. Vetter, a citizen of the United States, residing at Milwaukee, in the county of Milwaukee and State of Wisconsin, have invented a new, original, and ornamental Design for Merchandise Display Stand, of which the following is a specification, reference being had to the accompanying drawings, forming a part thereof.

In the drawing:

I claim:

The ornamental design for a merchandise display stand, as shown.

GERHARD J. VETTER.
